UNITED STATES PATENT OFFICE.

GEORGE REMNSNIDER, OF BELLEVILLE, ILLINOIS.

CONTROL FOR FLUID-FUEL BURNERS.

Application filed December 2, 1927. Serial No. 237,188.

My invention relates to a control for fluid fuel burners and particularly to that type of control or safety device in which the supply of fuel is automatically cut off whenever a predetermined amount of unconsumed oil has escaped from the burner either because of the extinction of the flame or from any other cause.

The object of my invention is to provide a simple and reliable device of the class referred to which will be particularly adapted for use in connection with domestic heating plants and similar oil burning devices receiving little or no skilled attention.

In the accompanying drawings, which illustrate one form of control device made in accordance with my invention, Figure 1 is a section taken on the line 1—1 of Figure 7, together with a diagrammatic representation of an oil burner to which the same is applied; Figure 2 is a side elevation; Figure 3 is a slightly enlarged section taken on the line 3—3 of Figure 5; Figure 4 is a section taken on the line 4—4 of Figure 7; Figure 5 is a top plan view, the valve casing, oil cup, and actuating weight being removed; Figure 6 is an enlarged side view of the rear end of the control lever; and Figure 7 is a top plan view of the complete device.

The various parts of the device are carried by a base plate 10 adapted to be secured by feet 11 to any suitable support and provided with upwardly extending wings 12 carrying the valve casing. This casing consists of a lower part 13 and an upper part 14 between which is clamped a corrugated resilient diaphragm 15 which is slightly sprung toward the part 13 for the purpose set forth in my Patent No. 1,550,047 granted August 18, 1925, and has a valve stem 16 secured in its center in the manner set forth in said patent. On the upper end of the stem is a conical valve 17 cooperating with an opening 18 in the upper part of the valve casing and its lower rounded end projects through a central aperture in the lower part of the casing. The opening 18 forms a communication between the oil chamber, formed between the upper part of the casing and the diaphragm, and the oil supply pipe 19. A pipe 20 leads from the oil chamber to the burner, diagrammatically shown at 21 (Figure 1) and the overflow pipe 22 of this burner discharges into the oil cup hereinafter to be described.

Pivoted to lugs 23 carried on the base is a plate 24, the upper face of which contacts with the rounded end of the valve stem 16 and the lower face of which is provided with a rounded projection 25. This projection bears on a plate 26 hinged at one end to the regulating lever 27 and provided at the other end with a lug 28 having an inclined face cooperating with the end of a screw 29 threaded in a lug 30 carried on the lever 27 to vary the inclination of the plate 26. The rear end of the lever 27 bears on an adjusting screw 31 threaded in the base and provided with a lock nut 32. Intermediate of its ends the lever is pivoted on a stud 33 on the base and is held in place by a stationary pointer 34 clamped against the end of the stud by a screw 35. The front end of the lever runs on a track 36 and is provided with a thumb piece 37 and with indicating numerals, as shown in Figures 5 and 7.

Supported on pivot bearings 38 is a lever 39 provided at one end with an oil cup 40 and at the other with a counterbalance 41. Pivoted in lugs 42 on the base is the actuating weight 43 having an arm 44 engaged by a trigger 45 on the counterbalance and a cam 46 adapted to actuate the plate 26. A stop 47 limits the downward movement of the outer end of the lever 39.

In adjusting my device the lever 27 is moved to its extreme right hand position so that the pointer indicates the numeral 0 on the lever. In this position the projection 25 will bear on the plate 26 directly over the axis of its hinge. The adjusting screw 31 is now rotated to raise the rear end of the lever until the valves 17 completely closes the opening 18 so as to prevent flow of oil from the supply pipe to the oil chamber and is secured in position by lock nut 32. This adjustment is permanent and the screw 31 need not thereafter be moved except to take up wear on the valve. The dimensions of the parts should be such that after their adjustment the lever will be slightly sprung in the direction of its length so that the resulting friction on the adjusting screw and track 36 will be sufficient to hold the lever in any position in which it is placed.

To adjust the device to the particular burner to which it is applied the lever 27 is moved to its extreme left hand position, as shown in Figure 7, in which position the projection 25 bears on the plate 26 at the end opposite the hinge. Screw 29 is now

moved in or out until the flow of oil is just sufficient for the maximum operation of the burner. By moving the lever more or less toward the right any oil flow from maximum to complete cut off can now be obtained. When the device is in operation if the flame should be extinguished or for any other reason excess oil should be delivered from the overflow pipe 22 it will accumulate in the cup 40 until its weight is sufficient to overcome the weight of the counterbalance 41 when the lever 39 will tilt on its fulcrum, as shown in dotted lines at the right hand side of Figure 1. This will cause the trigger 45 to be disengaged from the arm 44 so as to allow the actuating weight 43 to drop, as shown in dotted lines at the left hand side of Figure 1. When the weight drops the cam 42 will engage the free end of the plate 26 and raise it, thus seating the valve 17 and cutting off the oil supply. While raising the weight will open the valve the parts cannot be maintained in this position until the oil cup is emptied, which may readily be accomplished by lifting the lever 39, together with the attached weight and cup from its fulcrum.

Having fully described my invention, what I claim as new and desire to secure by Letters Patent of the United States is:

1. In a device of the class described, the combination with a valve, of a movable member for closing said valve, a control lever having an inclined face cooperating with said member to regulate the valve, and overflow actuated means operating on said member independently of the control lever to automatically close the valve.

2. In a device of the class described, the combination with a valve, of a movable member for closing said valve, a control lever having an adjustable inclined face cooperating with said member to regulate the valve, and overflow actuated means operating on said member independently of the control lever to automatically close the valve.

3. In a device of the class described, the combination with a base, of a valve casing supported thereon, a valve in said casing, a movable member arranged between said base and valve casing for actuating said valve, a control lever movable laterally between said base and member and cooperating with said member to regulate the valve, and overflow actuated means operating on said member independently of the control lever to automatically close the valve.

4. In a device of the class described, the combination with a base, of a valve casing supported thereon, a valve in said casing, a movable member arranged between said base and valve casing for actuating said valve, a control lever having an adjustable inclined face cooperating with said member to regulate the valve, and overflow actuated means operating on said member independently of the control lever to automatically close the valve.

5. In a device of the class described, the combination with a valve, of a movable member for closing said valve, a control lever, a plate carried by said lever and having an inclined face cooperating with said member to regulate the valve, means for varying the inclination of said face, and overflow actuated means operating on said member independently of the control lever to automatically close the valve.

6. In a device of the class described, the combination with a valve, of a movable member for closing said valve, a control lever, a plate carried by said lever and having an inclined face cooperating with said member to regulate the valve, means for varying the inclination of said face, independent means adjusting the face toward or away from said member without varying its inclination, and overflow actuated means operating on said member to automatically close the valve.

7. In a device of the class described, the combination with a base, of a valve casing supported thereon, a valve in said casing, a pivoted member for actuating said valve, a control lever arranged with one end adjacent to said member, a screw in the base for moving the end of said lever toward or away from said member, a plate hinged to said lever and having an inclined face cooperating with said member, means for varying the inclination of said face, and overflow actuated means operating on said member to automatically close the valve.

8. In a device of the class described, the combination with a valve, of a movable member for closing said valve, a control lever having an inclined face cooperating with said member to regulate the valve, an actuating weight provided with a cam cooperating with said member, and a tilting oil cup for releasing said weight to automatically close the valve.

In testimony whereof, I hereunto affix my signature, this 29th day of November, 1927.

GEORGE REMNSNIER.
